UNITED STATES PATENT OFFICE.

HENRY EYSTER HOKE, OF HANOVER, PENNSYLVANIA.

CAN-OPENER.

1,317,134.

specification of Letters Patent. Patented Sept. 23, 1919.

Application filed February 19, 1918, Serial No. 218,114. Renewed May 8, 1919. Serial No. 295,698.

To all whom it may concern:

Be it known that I, HENRY E. HOKE, a citizen of the United States, and a resident of Hanover, in the county of York and State 5 of Pennsylvania, have invented certain new and useful Improvements in Can-Openers, of which the following is a specification.

My invention relates to improvements in can openers and it consists in the constructions, combinations and arrangements herein 10 described and claimed.

An object of my invention is to provide a can opener including as one of the important features, a stop coöperating with the cutting 15 blade for spacing the cut an even distance from the rim of the can.

Another object of the invention is to provide a can opener including a pair of pivoted bars having a centering prong for centering the cutter in the middle of the can and providing a pivot, a blade carriage being 20 slidably mounted on the pivoted one of the bars, and a stop being provided for preventing the blade on the carriage from being struck by the centering prong under ordinary 25 conditions when the can opener is not in use.

Other objects and advantages will appear in the following specification, reference being 30 had to the accompanying drawing in which:

Figure 1 is a perspective view showing the improved can opener in use,

Fig. 2 is a detail section on the line 2—2 35 of Fig. 1,

Fig. 3 is a detail perspective view showing the correlated portions of the blade carriage disassembled,

Fig. 4 is a detail side elevation showing 40 the stop for preventing the blade from moving into the path of the centering prong,

Fig. 5 is a detail sectional view of a slight modification, and

Fig. 6 is a detail plan view of the parts 45 shown in Fig. 5.

In carrying out my invention I provide an anchor bar 1 having a centering prong 2 firmly fixed in the end thereof. A cutter bar 3 is pivoted on the centering prong 50 which thus forms the center or pivot for the cutter bar when the latter is forced around the periphery of a can to open the top, as will presently appear.

The centering prong 2 includes the square 55 portion 2^a which is firmly fixed in the bar 1. The centering prong is made round imme-

dately beneath this square portion and the cutter bar 3 rotates upon this rounded portion. A washer 2^b is interposed between the cutter bar 3 and a flange 2^c on the centering 60 prong. The flange 2^c is adapted to rest upon the top of the can and prevents contact of the adjacent edges of the cutter bar. The centering prong 2 extends off at an angle as illustrated in Fig. 2 and is made 65 pointed on the end to facilitate the forcing of the prong into the middle of the can.

Each bar has a carriage slidably mounted thereon. The anchor carriage 4 on the anchor bar 1 carries the anchor 5 which is simply in the nature of a prong also adapted to be forced into the top of the can. The carriage 4 is in the nature of a loop which almost embraces the bar 1 and is fitted tightly 70 upon the bar to maintain its position thereon when shoved along the bar in making an adjustment. The blade carriage 6 includes the upper and lower straps which have ears by means of which the straps are bolted together around the cutter bar. A 75 blade 7 is carried by the blade carriage and moves along the cutter bar with said carriage.

The blade 7 includes the right angled portion which occupies a position between the 85 lower strap 6 and the lower surface of the cutter bar 3. The bolts and nuts are tightened sufficiently to bind the blade carriage 6 on the cutter bar tightly enough to insure the blade carriage retaining various positions on the cutter bar when shoved into such 90 positions by the fingers.

A stop 8 is formed by a continuation of the blade 7, and the stop is so bent that it 95 engages the outer wall of the can and acts as a gage for preventing the blades 7 from accidentally creeping inwardly toward the center of the can top during the cutting operation. The provision of this stop 8 embodies one of the important features of the 100 invention, since without the stop 8 there would always be the possibility of the blade creeping inwardly and making an uneven cut. The stop 8 insures the uniform spacing of the cut from the rim or edge of the can. 105

Fixed in a suitable location on the cutter bar 3 is an abutment 9 which may simply consist of a pin as shown in Fig. 4. The purpose of the abutment 9 is to limit the movement of the blade carriage 6 toward the 110 pivotal extremity of the cutter bar. The reason for limiting the movement of the

blade carriage will be readily apparent in Fig. 4. Under ordinary conditions when the can opener is not in use, the several bars are free to swing around and consequently the centering prong 2 moves in a circular path beneath the cutter bar 3. Now were it not for the provision of the abutment 9, the centering prong 2 would swing around and strike the knife 7 forming notches in the cutting edge and possibly breaking the end of the blade off altogether. By providing the abutment 9 the blade 7 is prevented from entering the zone of movement of the centering prong 2 and consequently is an element of safety and contributes toward the general efficiency of the opener.

Substantially the same principle as regards the limiting of the movement of the blade carriage 6 is carried out in the modification shown in Fig. 5. Here the cutter bar 3 has a longitudinal slot 10 in which the end 11 of a stud 12 operates. When the pin is at the extremity of its movement toward the left, the blade carriage is consequently prevented from moving farther and so the contact of the centering prong 2 with the blade 7 is prevented. The stud 12 in this instance takes the place of the stop 8 in the other form of the invention, and is adapted to ride on the edge of the can to limit the inward movement of the cutter.

The stud includes a threaded portion 12^a which secures the blade carriage and blade together. The stud also includes a rounded portion on which a roller or sleeve 13 is mounted to lessen the friction between the stud and the edge of the can. In this construction, the blade carriage 6 is made substantially like the anchor carriage 4 in Fig. 1, in that it consists of a loop partly embracing the cutter bar as plainly shown in Fig. 6.

The operation of the can opener is as follows. When the can opener is first presented to a can, the anchor bar and cutter bar are close together. The centering prong 2 is first forced into the approximate center of the top of the can, whereupon the anchor and blade carriages 4 and 6 are moved into the proper positions with relationship to the edge of the can.

The anchor 5 and blade 7 are then simultaneously forced into the metal, care being taken that the stop 8 will come to the proper position on the outside of the can when the blade is forced into the metal. The anchor bar 1 now becomes a handle which is grasped in one hand to steady the can, while the cutter bar 3 is forced around with the centering prong 2 as a center therefor. When the cutter bar 3 has been carried around as far as the one hand can conveniently force it, the hands are changed and the cut is completed by the hand which formerly held the anchor bar.

It has been found that the cut capable of

being made by the use of this device, is smooth on both edges and is also perfectly even in contra-distinction to the usual uneven and jagged cut made by the ordinary can opener. The advantages of the stop 8 on the blade carriage need not be dwelt upon, it being perfectly obvious that it is desirable to make the cut at an even distance from the edge of the can all around. The stop 8 thus becomes a gage which insures a perfectly even and uniform cut.

The ease with which a broken blade may be replaced is also an outstanding feature of the invention. Should the blade 7 become broken, the strap portions of the carriage 6 may be readily taken apart by undoing the nuts so that a new blade may be set in place.

The facility with which a new blade may be secured on the blade carriage in the form shown in Fig. 5 is also apparent. The stud 12 performs the combined function of acting as a gage or stop, as previously pointed out, and also of holding the blade in position on the carriage. Both of the forms of the invention may be used to equal advantage, the form shown in Figs. 1 to 4 inclusive, however, being more simple, especially as regards the construction of the cutting blade. A handle is provided on the outer end of each of the bars 1 and 3. These handles may consist of wooden handles as illustrated in Fig. 1, or may be shaped up out of the metal of the bars themselves. In actual practice, these handles will consist simply of loops sufficiently large to enable a secure hold when the can opener is being used.

While the construction and arrangement of the can opener as illustrated in the drawing is that of a generally preferred form, obviously modifications and changes may be made without departing from the spirit of the invention or the scope of the claims.

I claim:—

1. In a can opener, a cutter bar having a slot, an anchor bar having a fixed centering prong providing a pivotal mounting for the cutter bar, a blade carriage slidable upon the cutter bar, a blade mounted on the carriage and adapted to penetrate the top of the can, a stud including a threaded portion for securing the carriage and blade together, and a pin portion for occupying said slot to limit the movement of the carriage toward the zone of movement of the centering prong, and a roller mounted upon said stud for engaging the edge of a can and preventing the inward movement of the blade toward the center of the top.

2. In a can opener, a cutter bar having a slot, an anchor bar having a fixed centering prong providing a pivotal mounting for the cutter bar, a blade carriage slidable upon the cutter bar, a blade mounted between the

carriage and cutter bar, a stud including a threaded portion for securing the carriage and blade together without binding the cutter bar, and an integral pin portion extending into said slot to limit the movement of the carriage toward the zone of movement of the centering prong, and a roller mounted upon said stud for engaging the edge of the can and preventing the inward movement of

10 the blade toward the center of the top.

3. The combination of elements constituting a can opener, consisting of a cutter bar, an anchor bar having an angularly extended centering prong fixed therein and arranged

to form the pivot for the cutter bar, a blade 15 carriage having a blade, unrestrictedly slideable on the cutter bar and adjustable to any diameter can top by simply moving the blade carriage with a finger, and means embodied in the cutter bar for stopping the blade 20 from entering the zone of rotation of the centering prong, thereby preventing the notching of the blade.
